[57] CLAIM

The ornamental design for a bottle stopper, as shown and described.

DESCRIPTION

FIG. 1 is a perspective view from the right side showing my new design;

FIG. 2 is a front elevational view thereof;

FIG. 3 is a bottom plan view thereof;

FIG. 4 is a top plan view thereof;

FIG. 5 is a right side elevational view thereof; and,

FIG. 6 is a rear elevational view thereof; and,

FIG. 7 is a left side elevational view thereof.

The broken lines showing the bottle in all the Figures are for purposes of context and form no part of the new design.
